(57) **CLAIM**

The ornamental design for an handle for surgical instrument, as shown and described.

DESCRIPTION

FIG. 1 is a perspective view showing my new design of the handle for surgical instrument design.

FIG. 2 is top plan view of the handle for surgical instrument design of FIG. 1, the bottom plan view being substantially the same.

FIG. 3 is a front elevation view thereof, the rear elevation view being substantially the same.

FIG. 4 is a right side elevation view thereof; and, FIG. 5 is a left side elevation view thereof.

The wire frame lines are intended to indicate surface contour and are not intended to be surface ornamentation.
